The ornamental design for a heavy duty stabilizer pad, as shown and described.

DESCRIPTION

FIG. 1 is a top, front, left side perspective view of a heavy duty stabilizer pad showing my new design;

FIG. 2 is a bottom, rear, right side perspective view thereof;
FIG. 3 is a top plan view thereof;

FIG. 4 is a bottom plan view thereof;

FIG. 5 is a left side elevational view thereof, the right side elevational view being a mirror image thereof;

FIG. 6 is a front elevational view thereof, the rear elevational view being a mirror image thereof; and,

FIG. 7 is a cross-sectional view taken along lines 3-3 of FIG. 3.

The broken lines illustrate portions of the heavy duty stabilizer pad that form no part of the claimed design.
